DESIGN FOR A HEATER CASING OR THE LIKE

Harry R. Trout, Pittsburgh, Pa., assignor to
American Radiator & Standard Sanitary Cor-
poration, New York, N. Y., a corporation of
Delaware

Application November 22, 1941, Serial No. 104,250

Term of patent 14 years

To all whom it may concern:

Be it known that I, Harry R. Trout, a citizen
of the United States, residing at Pittsburgh, in
the county of Allegheny and State of Pennsylvania,
have invented a new, original, and ornamental
Design for a Heater Casing or the like,
of which the following is a specification, refer-
ence being had to the accompanying drawing
forming part thereof.

In said drawing—

Fig. 1 is a top plan view of a heater casing or
the like embodying my new design;

Fig. 2 is a side elevational view thereof; and
Fig. 3 is a front elevational view thereof.

The characteristic features of the heater cas-
ing disclosed reside in the front door panels
having the configurations and associated in the
position shown.

I claim:

The ornamental design for a heater casing or
the like, as shown and described.

HARRY R. TROUT.
